WATER CLOSET

James R. Beam, New Castle, Pa., assignor to Universal Sanitary Manufacturing Co., New Castle, Pa., a corporation of Pennsylvania

Application September 30, 1935, Serial No. 42,966

1 Claim. (Cl. 4—73)

Under the conventional practice of starting siphonic action in water closets by means of a jet, the degree to which the jet is effective is dependent on the amount and velocity of water delivered to the jet less the friction resulting from flowing through the jet. Smooth channels having few turns are factors determining the velocity of the jet water, and it is the object of the present invention to provide a closet construction in which the water is delivered to the jet in a most direct manner, so that friction losses, which would otherwise lessen the velocity, are reduced to a minimum. Further, it is an object to provide a closet construction in which the rim jets perform only the wash-down function and in which the water, after delivery to the closet, is divided, a part passing to the rim and the remainder to the jet. Additionally, it is an object of the invention to provide a closet construction of the kind indicated, which is of simple form and, therefore, susceptible of cheap manufacture.

With this object in view, the invention consists in a construction and combination of parts, of which a preferred embodiment is illustrated in the accompanying drawing, wherein:

Figure 1 is a central vertical sectional view of a closet constructed in accordance with the invention.

Figures 2, 3 and 4 are sectional views on the planes indicated by the lines 2—2, 3—3 and 4—4 respectively of Figure 1.

In the present invention the jet 10 is disposed in the well 11 in facing relation to the intake 12 of the trap of the closet and the flush water is delivered to it from the intake chamber 13, which is disposed above the trap, whose globular formation where the up and down legs connect forms the bottom of the chamber. A jet chamber 14 is formed in the well of the closet and this chamber is in communication with the intake chamber 13 through channels or ducts 15 that may be secured either through drain casting or the insertion of clay partitions, but which are preferably secured by the superficial application of tubular conductors laid on the sides of the closet and incorporated with the latter by filling in around them before the closet is placed in the kiln. The conductors 15 communicate with the intake chamber 13 on opposite sides. Either one conductor 15 placed on one side of the closet may be employed or the conductor may be duplicated on the other side, as shown, in which case the flush water leaves the chamber 13 at similarly positioned points on opposite sides and in like manner enters the jet chamber 14.

When the flush tank is attached, the chamber 13 becomes inaccessible, but in each flushing of the closet, the chamber 13 is practically emptied, except for such water as may be trapped in the rear portion 16. The freezing of such trapped water, however, will not be attended with any injury to the closet, since the walls of the chamber 15 at the section 16 are generally divergent and, therefore, are relieved of any direct pressure by the forming ice.

Since the conductors 15, after application, become integral parts of the closet, the glazing operation results in complete concealment of them, as the filling in around the conductors prior to the glazing gives a general contour pleasing to the eye.

The superficial application of the conductors makes possible a placing of the intake and jet chambers in communication through ducts or channels that are free of slight projections that would constitute obstructions interfering with the free flow of the jet water and, therefore, reduce the velocity at which it is delivered to the jet.

The jet 10 is of generally oval form. This results in quick movement of the dead water in the up-leg of the trap and, therefore, in quick starting of siphonic action.

The wash-down function is accomplished by means of water delivered to the channel 17 formed in the rim 18, this channel being in communication with the intake chamber 13 through a port or opening 19. The rim on the under-side is formed with a series of spaced ports 20 which communicate with the channel 17. The ports 20 are downwardly inclined toward the inner face 35 of the bowl and are likewise inclined downwardly toward the left, considering the rim as being viewed from the top. In other words, the axes of the ports 20 are arranged to follow left-hand spirals in the surface of an imaginary cone, so that the water issuing through them will be given a left-hand swirl, thereby intensifying the natural water swirl in this latitude, which is left-handed.

In the flushing operation, when water is admitted to the entrance chamber 13 from the flush tank, one part passes through the port 19 to the channel 17 of the rim and the other part to the jet chamber 14, from which it issues in the form of a crescent shaped jet and passes into the up-leg of the trap. The amounts of water delivered respectively to the rim channel and the jet chamber are determined by the proper proportions of the conductors 15. If there be two of such conductors applied, one on each side of the closet, as shown, the capacity of each for a given quan-

ity of water need be only half that necessary to be provided where only one is used.

The jet, being in facing relation to the up-leg of the siphon, is above the level of the bottom of 5 the wall and the ducts 15, at every point, in their lengths are above the level of the well bottom. Thus the jet water does not have to move a great body of still water in starting the siphonic action, the arrangement being such that the jet has only 10 to start movement of the water in the up-leg of the siphon. This construction also provides for complete removal of the water when draining the closet, without having to take it from concealed 15 chambers. A siphon tube placed in the bottom of the well, by removing the water at that point, will completely remove all of the contained water, or the water may be removed readily by mopping it up.

Having described the invention, what is claimed as new and useful is:

A water closet bowl having a trap with its intake in the well thereof, a jet disposed in the well in facing relation to the intake of the trap but above 5 the plane of the bottom of the well, and a water intake chamber disposed on top of the trap and on the opposite side of the bowl from the jet but above the plane of the latter, the bowl having ducts incorporated therewith to place the intake 10 chamber in communication with the trap, the ducts extending around the bowl from the chamber to the jet at a gradual inclination with no points in their lengths being below the plane of the jet. 15
